BENJAMIN E. STEVENSON AND MARY E. STEVENSON, OF REDDING, CALIFORNIA.

ROTARY ENGINE.

1,164,136.

Specification of Letters Patent. Patented Dec. 14, 1915.

Application filed February 17, 1915. Serial No. 8,730.

To all whom it may concern:

Be it known that we, BENJAMIN E. STEVENSON and MARY E. STEVENSON, both citizens of the United States, residing at 5 Redding, in the county of Shasta and State of California, have invented new and useful Improvements in Rotary Engines, of which the following is a specification.

This invention relates to prime movers 10 and particularly to an engine of the rotary type and operative by expansive fluid.

It is an object of the invention to provide a rotary motor with a stationary casing having a pressure chamber, and a rotor mounted eccentrically therein with a valve in the form of a ring surrounding the rotor, and carrying an oscillating abutment member 15 slidably engaging the rotor, operative to control the admission of operating fluid 20 from the pressure chamber.

It is also an object of the invention to provide an internal combustion engine in which there is a casing with an explosion chamber and a cylindrical chamber in which is 25 fitted an annular valve operative to separate the chambers and to control the admission of pressure to a rotary abutment member connected to and operating a rotor and its shaft, and to provide suitable inlet, transfer relief and exhaust valves for controlling 30 the flow of vapor and gases.

The invention consists of the parts and the combination and construction of parts as hereinafter more fully described and 35 claimed, having reference to the accompanying drawings, in which—

Figure 1 is an elevation of the engine partly broken away. Fig. 2 is a vertical transverse section, showing the casing in 40 elevation, showing the piston in the working or pressure cycle. Fig. 3 is a transverse section showing the casing side plates in position. Fig. 4 is a transverse section showing the intake and exhaust valves in 45 section. Fig. 5 is a diagram with piston in first revolution. Fig. 6 is a diagram with piston in second revolution. Fig. 7 shows a double ported ring-valve.

The engine comprises one or more power 50 units each including a suitable annular casting 2 of separable sections and having side plates divided into upper and lower sections 3—4. The lower sections are adapted to be bolted endwise to adjacent parallel casings 55 2 and to form journals for a shaft 5 which

is eccentric to the common axis of the casings 2.

The casing is provided at a suitable location with a pressure chamber 6 in which a combustible vapor is exploded, when the 60 engine is operating on the explosive principle, by a sparking device 7. This chamber 6 is adapted to communicate with the interior bore of the casing through a port 8, Fig. 2. Turnably fitting the bore of the 65 casing 2 is a throttle valve 9 in the form of a thin, wide ring having a radial port 10 with an extended peripheral canal 11' adapted to sweep beneath the port 8 once in each revolution. Fast on, or formed with 70 the shaft 5 is a rotor 11 of such diameter as to have a running contact with the concaved surface of the valve ring 9. The difference between the diameters of the rotor 11 and of the bore of the ring 9 forms a crescent- 75 shaped chamber 9'. The valve ring 9 and the rotor are operatively connected by a vane or abutment 12 which is pivoted to the ring just ahead of the port 10, as at 13, and is slidably mounted at the diameter of and 80 in the rotor 11. In this drawing the moving parts rotate clockwise, and the port 8 is so disposed as to be nearly tangential to the circumference of the valve ring 9 and so movement of fluid from chamber 6 is directed with the motion of the ring and the 85 vane.

When operating as a steam engine, steam is admitted from chamber 6 to act upon the 90 vane 12 as the port 10 coincides with the port 8 and the steam is not cut off until the 95 canal 11' passes. Exhaust from the rotor chamber is provided by a port 14 in one side 3 which may be controlled by a valve 15 and its operating shaft 16.

For operating the motor by the combustion of vapor in chamber 6, an intake port 17 is provided at a suitable location, here shown as below the pressure port 8, and entering the crescent rotor chamber 9' through the casing side 3. The intake port is controlled by an automatically closing valve 18 operable by the cam shaft 16. If the intake valve be open then as the vane swings down past the port 17 a suction effect results and will draw in a charge of fuel (vapor or gas) from a suitable source; the exhaust valve 15 being open to prevent back pressure against the rotating piston 12. The intake revolution may be considered the first revolution of the 100 110

rotor. On the next revolution, or second revolution, the vapor in front of the vane 12 is displaced from the crescent chamber, passed through a transfer tube 19, and is compressed in the combustion chamber 6 and exploded by the sparking device 7 at a suitable time. The exhaust valve is closed during the compression stroke.

The pressure of the exploded vapor acts 10 through port 8 and as the valve ring 9 revolves with the rotor its port 10 opens port 8 to the space behind the upper surface of the piston 12 and the pressure acts thereon during the third revolution of the rotor. 15 The canal 11' permits a complete expansion of the exploded vapor, during the turning of the ring valve, against the piston. During this revolution the exhaust valve is open to prevent back pressure. When the piston 20 starts its second, or compression revolution, the production of a vacuum behind the piston 12 is prevented by providing a relief port and valves 20 for admitting air into the rotor chamber. It will be seen that during 25 the intake stroke immediately following working or expansion revolution the burnt gases will be cleared from the rotor chamber by the rotating piston. The engine casing being divided into separable upper and lower sections permits the rotors and shaft to be readily lifted from the lower journals when the upper parts are removed. The several mechanically operated valves, except the ring valve, are mounted on and in the upper casing parts and the cam shaft on the lower parts thus facilitating and increasing accessibility. It is understood that any number of explosions per shaft revolution may be had by multiplying the number of individual units.

It is peculiar of this motor that there are no reciprocating parts utilized in the power chamber and therefore the engine can safely and readily attain very high speeds. While 45 the piston 12 has a sliding motion as to the rotor, it in reality rotates about the rotor axis with the rotor. Another important feature of the engine is the rotating ring-valve with its radial port and the circumferential connecting canal 11' which maintains communication between the combustion chamber and the rotor chamber. The ring-valve is preferably supported on ball-bearings 21 to reduce friction and has peripheral 50 packing rings 22 to reduce pressure loss. If desired the ring-valve may be utilized in a reversible steam motor by providing it with a plurality of the radial ports 10 each having its canal or groove 11' extended oppositely to 55 the other, as in Fig. 7.

Having thus described our invention what we claim and desire to secure by Letters Patent is—

1. A rotary combustion engine comprising 65 a casing having a fluid admission port,

a ring valve mounted concentrically within the casing and provided with a port adapted to register with the casing port, a rotor eccentrically arranged within the casing and ring valve and formed with a recess, and a vane slidable in the recess of rotor and having its outer end positively connected to the inner periphery of the ring. 70

2. A rotary combustion engine comprising a casing having a cylindrical bore and pressure chamber connected by a port, a ring valve mounted in the bore and provided with a port capable of registering with the casing port, said ring valve being provided on its inner periphery and in advance of its port with a projection, a rotor eccentrically disposed within the casing and valve and formed with a recess, and a vane slidable in the recess of the rotor and pivotally engaging with the projection of the ring valve. 75

3. A rotary combustion engine comprising a casing having a cylindrical bore and pressure chamber connected by a port, a ring valve mounted in the bore and provided with a port capable of registering with the casing port, said ring valve being provided on its inner periphery and in advance of its port with a projection and on its outer periphery with a circumferential canal extending rearwardly from its port and adapted to pass over the casing port, a rotor eccentrically disposed within the casing and valve and formed with a recess, and a vane slidable in the recess of the rotor and pivotally engaging with the projection of the ring valve. 80

4. A rotary combustion engine comprising a casing having a cylindrical bore and a pressure chamber communicating with the bore through an approximate tangential port, the bore of the casing being provided with intake and exhaust ports and a transfer passage between the bore and pressure chamber, a ring valve concentric within the bore for controlling the tangential port, 105 a rotor eccentrically mounted in the ring valve, and a vane movably connecting the rotor to the ring valve.

5. A rotary combustion engine comprising a casing having a cylindrical bore and a pressure chamber communicating with the bore through an approximate tangential port, a concentric ring valve arranged in the bore of the casing and having a port provided with a rearwardly extending and outwardly inclined peripheral canal adapted to pass over the tangential port of the casing, a rotor eccentric within the ring valve, and a vane movably carried by the rotor and connected to the ring valve in advance of 110 the port therein. 120

6. A rotary combustion engine comprising a casing having a cylindrical bore and a pressure chamber communicating with the bore through an approximate tangential 125

- port, the bore of the casing being provided with intake and exhaust ports and a transfer passage between the bore and pressure chamber, a ring valve concentric within the bore for controlling the tangential port, a rotor eccentrically mounted in the ring valve, a vane movably connecting the rotor to the ring valve, a valve controlling the transfer passage between the bore and pressure chamber, means for controlling the valve last mentioned to open the passage for compressing the gas in the pressure chamber during one revolution of the rotor, and a sparking device for exploding the compressed gas in the pressure chamber.
7. A rotary combustion engine comprising a casing having a cylindrical bore and a pressure chamber communicating with the bore through an approximate tangential port, the bore of the casing being provided with intake and exhaust ports and a transfer passage between the bore and pressure chamber, a ring valve concentric within the bore for controlling the tangential port, a rotor eccentrically mounted in the ring valve, a vane movably connecting the rotor to the ring valve, a valve controlling the transfer passage between the bore and pressure chamber, a valve in each of the intake and exhaust ports, a sparking device in the pressure chamber, and means for operating the valves and sparking device to successively intake, transfer and compress, explode and exhaust.
8. A rotary combustion engine comprising a casing with a bore and an explosion chamber connected thereto by a port, a sparking device in the sparking chamber, a rotor mounted in the bore of the casing, intake and exhaust ports in the bore of the casing, a transfer passage leading from the bore to the chamber whereby the rotor may take the gas from the intake and compress it in the chamber, valves for the connecting port, transfer passage and intake and exhaust ports, means for opening the valves in the intake port, transfer passage and exhaust port successively, and means for operating the sparking device subsequent to compression of the gas in the chamber and after opening and closing of the transfer passage valve.
9. In testimony whereof we have hereunto set our hands in the presence of two subscribing witnesses.
